UNITED STATES PATENT OFFICE.

ALBERT L. GAINER, OF ST. LOUIS, MISSOURI.

TRAIN-STOPPING APPARATUS.

1,131,502.

Specification of Letters Patent.

Patented Mar. 9, 1915.

Application filed July 17, 1914. Serial No. 851,607.

To all whom it may concern:

Be it known that I, ALBERT L. GAINER, a citizen of the United States, residing at St. Louis, in the State of Missouri, have invented new and useful Improvements in Train-Stopping Apparatus, of which the following is a specification.

This invention relates to improvements in train stopping apparatus and has particular application to train controlled apparatus of this character.

In carrying out the present invention, it is my purpose to provide train stopping apparatus which will embody among other features a track obstacle capable of movement to active and inactive positions and adapted to actuate car carried mechanism when in active position to cut off the propelling power of the motor car and effect an application of the brakes, and a fluid motor for actuating such obstacle to active position and connected with a source of supply, means being provided for establishing communication between the motor and source and holding the fluid within the motor whereby the obstacle will remain in inactive position succeeding the cutting off of communication between the motor and source of supply, means being also provided for releasing the fluid from the motor so that the obstacle may be restored to normal inactive position.

It is also my purpose to provide apparatus of the type set forth which may be stalled and maintained at a minimum expense, which will operate efficiently and effectively under all conditions and whereby the propelling power of a motor car or train will be cut off and the brakes applied in the event of such car entering the danger zone.

With the above and other objects in view, the invention consists in the construction, combination and arrangement of parts hereinafter set forth in and falling within the scope of the claims.

In the accompanying drawings: Figure 1 is a top plan view of a trackway showing the track portion train controlled apparatus installed. Fig. 2 is a cross sectional view therethrough showing the tie carrying the obstacle and fluid motor. Fig. 3 is a sectional view on the line 3—3 of Fig. 2. Fig. 4 is a longitudinal sectional view through the tie carrying the valve controlling communication between the fluid motor and

source of supply. Fig. 5 is a similar view through the tie carrying the relief valve. Fig. 6 is a diagrammatic sectional view. Fig. 7 is a horizontal sectional view on the line 7—7 of Fig. 2. Fig. 8 is a diagrammatic view of the car carried mechanism.

Referring now to the drawings in detail, 1 designates a trackway composed of transversely disposed ties 2 appropriately spaced 65 apart and parallel lines of rails 3 secured to the upper surfaces of the ties in some suitable manner.

In the present instance, each tie 2 comprises a bottom longitudinal section 4 having upwardly projecting side and end walls 5 and 6 respectively, and a top longitudinal section 7 formed with downwardly extending side and end walls 8 and 9 respectively overlapping the side and end walls of the bottom section and telescoping thereover. Interposed between the confronting faces of the bottom and top walls of the tie are coiled expansion springs 10 serving to maintain the upper section 7 elevated and restore 80 the same to elevated position succeeding the downward movement thereof under the weight of the rolling stock operating over the lines of rails. Certain of the ties 2 have the lower walls thereof provided centrally 85 with threaded openings 11 and threaded through the opening in each of such ties and projecting upwardly within the tie is a cylinder 12 within which is mounted for sliding movement a piston 13 equipped with 90 a piston rod 14 extending through the upper end of the cylinder and equipped with an obstacle 15 working through an opening formed in the top wall of the tie and alining axially with the cylinder. Encircling the 95 piston rod 14 is a coiled expansion spring 16 having the upper end thereof abutting the adjacent end wall of the cylinder and the lower end engaging the confronting face of the piston, such spring acting to maintain the piston at the lower end of the cylinder and so hold the obstacle 15 in inactive position. Each cylinder 12, piston 13 therein and piston rod 14 forms a fluid 100 motor controlling the obstacle 15 and the ties carrying such motors and obstacles are spaced apart appropriate distances along the trackway, say, for instance, two miles.

Leading from the lower end of each cylinder 11 is a supply pipe 17 extending forwardly from the cylinder a suitable distance, say, for example, five-hundred feet. The

outer end of each pipe 17 is connected with the upper extremity of a vertical tube 18 passed through alining openings formed in the top and bottom walls of the adjacent tie 2 and the lower end of the tube 18 is tapped onto a supply main 19 connected up with a suitable source of fluid supply such as air. Located in the tube 18 is a controlling valve 19' provided with an outwardly projecting horizontal handle 20 connected with the lower end of a link 21, the latter having the upper end thereof pivotally connected with a block 22 depending from the inner surface of the top wall of the tie. One of the ties a suitable distance in advance of the tie carrying the controlling valve 19' is equipped with a vertically disposed exhaust tube 23 mounted in vertically alining openings in the top and bottom walls respectively of the tie and located in the tube 23 is a normally closed relief valve 24 provided with an outwardly projecting horizontal handle 25 pivotally connected with the lower end of a vertical link 26, such link having the upper end thereof pivotally connected with a block 27 depending from the inner face of the top wall of the section 7 of the tie. The lower end of each exhaust tube 23 is connected by way of an exhaust pipe 28 with the lower end of the second cylinder behind that immediately at the rear of the particular exhaust tube, as clearly illustrated in Fig. 6 of the drawings. Tapped onto each exhaust pipe 28 immediately in advance of the motor connected with such pipe and extending upwardly therefrom is a vertical branch pipe 29 equipped at its upper end with a manually operable relief valve 30.

In the present instance, I have illustrated the car carried mechanism as installed in a steam driven locomotive and in this connection I wish it to be understood that this mechanism is equally applicable to electrically operated motor cars. In this case, the car carried mechanism comprises pipes 32, 32 leading from the drive cylinders of the locomotive and connected with a common exhaust pipe 33 equipped with a valve 34 provided with a horizontally disposed handle 35. Connected in the brake pipe or train line air pipe of the air brake system of the train is a releasing valve 36 equipped with a horizontally disposed handle 37.

In practice, as a car or train moves over the trackway the sections 7 of the ties give or yield and move downwardly on the sections 4 against the action of the springs 10 thereby eliminating shock and jar to the rolling stock. When a motor car or train passes over the tie carrying the controlling valve 19, the section 7 of such tie moves downwardly and in the downward movement thereof actuates the valve 19' to open position, through the medium of the link 21

and handle 20. When the valve 19' is open, communication is established between the cylinder 11 behind the controlling valve and the source of supply so that air flows into such cylinder and slides the piston 13 upwardly therein against the action of the spring 16 thereby moving the obstacle 14 to elevated or active position. Immediately that the tie carrying the controlling valve is relieved of the weight of the motor car or train the springs 10 react and so restore the sections 7 to normal position thereby closing the valve 19' and cutting off communication between the source of supply and the particular motor. As the valve 19' moves to cut off position the air below the piston of the motor is trapped within the latter and so holds the piston elevated against the action of the spring. Should a second train pass the active obstacle 15 the latter will contact with the valve handles 35 and 37 thereby opening the valves 34 and 36 respectively with the effect to place the engine cylinders in communication with the atmosphere and bleed the brake pipe or train line air pipe. Thus, the force of the propelling fluid on the drive pistons of the engine is reduced, and the brakes applied to the wheels.

When the leading train passes over the tie carrying the relief valve 24 of the sections 7, such tie moves downwardly under the weight of the rolling stock against the action of the springs 10 thereby opening the valve 24 through the action of the link 26 and handle 25. Upon the opening of the valve 24 communication is established between the lower end of the particular cylinder controlled by such valve and the atmosphere thereby releasing the air from the motor and permitting the spring 16 to react and restore the piston to normal position.

Should it be desired to reverse the direction of travel of the leading train after the obstacle behind such train has moved to active position, the valve 30 is opened so that the air is discharged from the cylinder and the obstacle rendered inactive, thereby enabling the train to move in the desired direction.

From the foregoing description taken in connection with the accompanying drawings, the construction and mode of operation of my improved train stopping apparatus will be readily apparent. It will be seen that I have provided a train stopping apparatus which is train controlled and entirely automatic in operation and whereby the propelling power of trains will be automatically cut off and the brakes applied in the event of such trains entering the danger zone.

While I have herein shown and described one preferred form of my invention by way

of illustration, I wish it to be understood that I do not limit or confine myself to the precise details of construction herein described and delineated, as modification 5 and variation may be made within the scope of the claims without departing from the spirit of the invention.

I claim:

1. In train stopping apparatus, a track-way comprising ties each formed of a stationary section and a movable section, tension means holding said movable section in normal position and permitting such section to move under the weight of the rolling stock, track obstacles carried by certain of said ties and spaced apart, fluid motors for actuating said obstacles to active position, a source of supply for said motors, valves controlling communication between said motors and source and carried by certain of the remaining ties and each disposed in advance of the motor controlled thereby, and a connection between each valve and the movable section of the tie carrying the same whereby the valve will be opened in the passage of the rolling stock over the tie.
2. In train stopping apparatus, a track-way comprising ties each formed of a stationary section and a movable section, tension means holding said movable section in normal position and permitting such section to move under the weight of the rolling stock, track obstacles carried by certain of said ties and spaced apart, fluid motors for actuating said obstacles to active position, a source of supply for said motors, valves controlling communication between said motors and source and carried by certain of the remaining ties and each disposed in advance of the motor controlled thereby, a connection between each valve and the movable section of the tie carrying the same whereby the valve will be opened in the passage of the rolling stock over the tie, relief valves carried by certain of the remaining ties and controlling communication between the motors and the atmosphere, each relief valve being disposed in advance of the motor controlled thereby, a connection between each relief valve and the movable section of the tie carrying the same whereby the motor will be opened to the atmosphere in the passage of the rolling stock over the tie, and means for moving the obstacle to inactive position succeeding the opening of the relief valve.

maining ties and controlling communication between the motors and the atmosphere, each relief valve being disposed in advance of the motor controlled thereby, and a connection between each relief valve and the 50 movable section of the tie carrying the same whereby the motor will be opened to the atmosphere in the passage of the rolling stock over the tie.

3. In train stopping apparatus, a track-way comprising ties each formed of a stationary section and a movable section, tension means holding said movable section in normal position and permitting such section to move under the weight of the 55 rolling stock, track obstacles carried by certain of said ties and spaced apart, fluid motors for actuating said obstacles to active position, a source of supply for said motors, valves controlling communication 60 between said motors and source and carried by certain of the remaining ties and each disposed in advance of the motor controlled thereby, a connection between each valve and the movable section of the tie carrying 65 the same whereby the valve will be opened in the passage of the rolling stock over the tie, relief valves carried by certain of the remaining ties and controlling communication between the motors and the atmosphere, each 70 relief valve being disposed in advance of the motor controlled thereby, a connection between each relief valve and the movable section of the tie carrying the same whereby the motor will be opened to the atmosphere 75 in the passage of the rolling stock over the tie, and means for moving the obstacle to inactive position succeeding the opening of the relief valve.

In testimony whereof I affix my signature 85 in presence of two witnesses.

ALBERT L. GAINER.
